UNITED STATES PATENT OFFICE.

BENJAMIN M. LEVOY, OF NEW YORK, N. Y.

EYEGLASSES.

SPECIFICATION forming part of Letters Patent No. 768,609, dated August 30, 1904.

Application filed May 2, 1904. Serial No. 205,947. (No model.)

To all whom it may concern:

Be it known that I, BENJAMIN M. LEVOY, a citizen of the United States, residing at New York city, borough of Manhattan, and State of New York, have invented certain new and useful Improvements in Eyeglasses, of which the following is a specification, reference being had therein to the accompanying drawings.

This invention relates to improvements in eyeglasses, and has for its primary object the provision of what is commonly known as a "box-clamp," possessing novel characteristics which facilitate a rigid clamping of the nose-guard and spring therewithin.

15 A convenient embodiment of the invention comprises a box-clamp open at one side and having oppositely-disposed inwardly-diverging walls or surfaces adjacent to said open side and so arranged that when the opposite walls of the clamp are forced together by suitable means the nose-guard and spring or either of them will be firmly embraced both sidewise and edgewise, thereby effectually preventing any possible play of the same in either 20 of these directions.

The improved details in the construction and arrangement of the several parts of the device will be apparent from the detailed description hereinafter when read in connection 30 with the accompanying drawings, forming part hereof, and wherein the above-mentioned embodiment of the invention is clearly illustrated.

In the drawings, Figure 1 is a rear elevation of a pair of eyeglasses provided with the present improvements. Fig. 2 is a longitudinal sectional view through the clamp and its stud or shank. Fig. 3 is a view similar to Fig. 2 of a slightly-modified form of device, 40 and Fig. 4 is a like view of a still further modification.

Referring more specifically to the drawings, wherein like reference characters refer to corresponding parts in the several views, A designates the box-clamp open at one side, as at *a*, B the stud or shank projecting outwardly from one of the walls thereof, and C the lens-clamping jaws carried by the stud.

D represents the usual bow-spring, and E the nose-guards.

The outer and inner walls of the clamp, respectively indicated at F and F', are perforated at *f* in alinement with the screw-threaded bore *b* of the stud B, provided for the reception of a binding-screw G, headed at its outer end, so as to impinge upon the outer surface of the wall F of the clamp, and having a threaded engagement with said bore *b*. With reference more particularly to Fig. 2, H represents beveled portions of the walls F F', the same being interiorly arranged and converging outwardly to the side opening *a*. From this construction it will be appreciated that upon the insertion of the securing portion or shank *e* of the guard E and the end of the spring D, both of them having centrally-disposed apertures or slots *d* of sufficient size for the purpose, the tightening of the screw G will draw the walls of the clamp together, thereby causing them to impinge upon said shank *e* and spring, thus firmly holding the same against sidewise movement, and the inclined walls H will force the same inwardly to effect a binding action between said surfaces and the rear wall *a'* of the clamp, which will prevent any edgewise movement of the spring or guard. Filling-pieces or enlargements I at the inner corners of the clamp facilitate the binding action upon the parts to be held, as well as overcoming any liability or tendency of the parts to tilt or separate at their inner edges. It is believed, however, that in practice these pieces I may be dispensed with.

The differentiating characteristic of the structure shown in Fig. 3 as compared with that before described resides in the fact that the entire inner surfaces H' of the walls F F' are inclined, diverging from front to rear, while the device of Fig. 4 differs from both the preceding forms in that the beveled or inclined surfaces are provided through the medium of inserts H'', seated behind lips or lugs J, adjoining the side opening represented at *j* in this figure.

From the above description it will be noted

that the invention is rather comprehensive in character and that various changes and alterations may be made in the details of construction herein disclosed without departing from 5 the spirit of the invention.

Having thus described the invention, what I claim as new, and desire to secure by Letters Patent, is—

1. A box-clamp of the character described 10 open at one side and having oppositely-disposed normally inwardly diverging walls or surfaces adjacent to said open side.
2. A box-clamp of the character described 15 open at one side and having oppositely-disposed adjustable clamping-walls one of which is normally inclined inwardly.
3. A box-clamp of the character described 20 open at one side and having oppositely-disposed normally inwardly diverging walls or surfaces adjacent to said open side, said walls having alined apertures.
4. A box-clamp of the character described 25 having oppositely-disposed adjustable normally inwardly diverging walls or surfaces.
5. A box-clamp of the character described 30 having oppositely-disposed normally inwardly diverging walls or surfaces, the same having alined apertures.
6. A box-clamp of the character described 35 open at one side and having oppositely-disposed inwardly-diverging walls or surfaces adjacent to said open side, and filling-pieces or enlargements at the inner corners of the clamps.
7. A box-clamp of the character described 40 having oppositely-disposed walls formed to clamp both inwardly and laterally.
8. A box-clamp of the character described 45 having oppositely-disposed walls formed to

clamp both inwardly and laterally in combination with means for adjusting said walls.

9. A box-clamp of the character described 45 having oppositely-disposed apertured binding-walls, and a stud or shank projecting from one of said walls and having a screw-threaded bore in alinement with the apertures in the walls.

10. In combination with a shank, a box-clamp therefor, said clamp being open at one side and formed with an inclined portion adjoining said opening impinging upon the outer edge or corner of said shank.

11. In combination with a shank, a box-clamp therefor, said clamp being open at one side and formed with an inclined portion adjoining said opening impinging upon the outer edge or corner of said shank in combination with a binding-screw passing loosely through an aperture in the shank.

12. In combination with a shank, a box-clamp therefor, said clamp being open at one side and formed with an inclined portion adjoining said opening impinging upon the outer edge or corner of said shank in combination with fastening means.

13. A box-clamp of the character described 60 having oppositely-disposed apertured binding-walls open at one side, and a stud or shank projecting from one of said walls and having a screw-threaded bore in alinement with the 65 apertures in the walls.

In testimony whereof I affix my signature in presence of two witnesses.

BENJAMIN M. LEVOY.
